4 FIG.2.

FIG.3.

FIG.4.

FIG. 1 is a front elevational view of a combined container and artificial fingernails showing my new design in an open condition;

FIG. 2 is a top plan view thereof;

FIG. 3 is an end elevational view thereof; and

FIG. 4 is a section taken on line 4—4 of FIG. 2.

The top, bottom and sides of the container are of flat planar configuration.

The diagonal shade lines in FIG. 2 represent a transparent cover over the artificial fingernails at the front of the container tray.

I claim:

The ornamental design for a combined container and artificial fingernails, as shown and described.
